UNITED STATES PATENT OFFICE.

NIRA J. HAWKS, OF NEW YORK, N. Y.

DESIGN FOR A COMBINATION-TOOL.

49,994.

Specification for Design.

Patented Dec. 5, 1916.

Application filed August 14, 1915. Serial No. 45,598. Term of patent 14 years.

To all whom it may concern:

Be it known that I, NIRA J. HAWKS, a citizen of the United States, residing at New York, county and State of New York, have invented a new, original, and ornamental Design for Combination-Tools, of which the following is a specification, reference being had to the accompanying drawing, forming part thereof.

The figure is a plan view of a combination tool, embodying my new design.

The appearance in detail of the design will

be clear from the drawing, there being particular prominence in the open framework 1, and projections 2, 3 and 4 at one end adjacent to which is disposed a circular disk 5, and a sharp point 6 at the other end.

I claim:

The ornamental design for a combination tool, as shown and described.

NIRA J. HAWKS.
